LEAD FOR BLACK-LEAD, COLORED, AND
COPYING PENCILS AND THE LIKE

Richard Zückert, Bohmisch-Budweis, Czechoslovakia, assignor to the firm "Koh-i-noor" tužkárna L. & C. Hardtmuth, Ces. Budejovice, Czechoslovakia

Application January 27, 1939, Serial No. 253,621
In Germany May 30, 1936

1 Claim. (Cl. 120—33)

This invention relates to a lead for black-lead, colored and copying pencils and the like which is cemented in a cover. In the case of such leads it is desirable that their surface allows of good 5 cementing to the cover; on the other hand the lead must slide smoothly over the paper when writing. These two requirements are difficult to fulfill simultaneously as the smooth writing requires a minimum number of pores in the lead whereas the cementing adheres the tighter the 10 more pores are in the periphery of the lead.

This objection is overcome according to the invention in that in the outer layer of the lead artificially produced hollow spaces are provided. 15 Some of these hollow spaces are located directly in the surface of the lead and each of such points forms an artificial pore of larger or smaller diameter which assists the adhesion between the lead and casing during the glueing operation. 20 An advantageous method for the production of the lead according to the invention consists in fitting in the outer layer of the ordinary lead composition body distributed nest-shaped inserts which contain a substance which easily liberates 25 gas, in compressing this mixed composition body to the shape of a lead in the usual manner, and in finally subjecting the lead thus obtained to a treatment liberating the gas, which treatment may consist of a vacuum treatment, a drying 30 treatment, a heat treatment or the like. Naphthalene in powdered state may be used for example as substance easily liberating gas.

An embodiment of the invention is illustrated by way of example in the accompanying drawing in which—

Fig. 1 shows a lead in cross-section on a considerably enlarged scale.

Fig. 2 is a section on line II—II through the end of the lead shown in Fig. 1.

Fig. 3 illustrates the production of this lead in a lead press of known type.

Fig. 4 is a cross-section through the lead composition taken on line IV—IV of Fig. 3.

The lead 1 in Figs. 1 and 2 has in its peripheral layer indiscriminately distributed nest-shaped hollow spaces 2. Some of these hollow spaces are located on the surface of the lead and these hollow spaces form artificial pores of different depths and different diameters. In the production of the lead according to the process illustrated in Figs. 3 and 4 the outermost layer 3 of the lead composition body is provided with nest-shaped inserts 5 containing a material easily liberating gas (Fig. 4). The mixed composition body thus obtained is introduced into the usual press cylinder in the shape of a lead 8. The lead 8 thus pressed has a cross-section similar to that shown in Figs. 1 and 2, but with the difference that at the points where hollow spaces are to be subsequently formed, there are for the time being inserts of the gas-liberating substance. These hollow spaces are only formed when the lead is subjected to a treatment causing the liberation of gas.

I claim:

A process of manufacturing leads for pencils, color-pencils, copying-pencils or the like for use in cemented cover, consisting in providing in the outermost portion of the commonly used lead-composition-body inserts containing a substance easily liberating gas, in pressing to the form of a lead the lead-composition thus prepared, and in treating this lead in a suitable manner for causing the liberation of gas.

RICHARD ZÜCKERT.
